TAPE DISPENSER

Jean O. Reinecke, Pasadena, Calif., and Geno C. D'Ercoli, Park Forest, and Michael S. Joss, Skokie, Ill., assignors to Minnesota Mining and Manufacturing Company, St. Paul, Minn.

Filed Oct. 26, 1971, Ser. No. 192,688

Term of patent 14 years

Int. Cl. D19—02

U.S. Cl. D74—1

FIG. 1

FIG. 5

FIG. 2

FIG. 4

FIG. 3

FIG. 6

FIG. 1 is a perspective view of the tape dispenser showing our new design;

FIG. 2 is a top plan view of the tape dispenser of FIG. 1;

FIG. 3 is a side elevational view of the tape dispenser of the invention, the other side being identical to the side illustrated;

FIG. 4 is an end elevational view of the tape dispenser of FIG. 3, viewed from the left thereof;

FIG. 5 is an end elevational view of the tape dispenser of FIG. 3, viewed from the right thereof; and

FIG. 6 is a bottom plan view of the tape dispenser of FIG. 3.

We claim:

The ornamental design for a tape dispenser, substantially as shown and described.
